CLAIM

The ornamental design for a shopping cart as shown and described.

DESCRIPTION

This application is related to and incorporates by reference U.S. patent application Ser. No. 29/857,743, filed on Oct. 25, 2022. It is understood that any material in U.S. patent application Ser. No. 29/857,743 that is not present in this application forms no part of the claimed design.

FIG. 1 is a top, rear perspective view of the shopping cart showing our new design;

FIG. 2 is a front view thereof;

FIG. 3 is a rear view thereof;

FIG. 4 is a right side view thereof;

FIG. 5 is a top view thereof;

FIG. 6 is a bottom view thereof; and,

FIG. 7 is left side view thereof.

In the drawings, the features shown in broken lines are portions of the shopping cart forming no part of the claimed design. The bolded broken lines in the figures indicate the bounds of the claimed design and form no part of the claimed design.
